U.S. Cl. D9—111

FIG. 1 is an elevational view of a bottle or similar article showing our new design, the view from the opposite side being the mirror image of that shown;

FIG. 2 is a bottom plan view thereof;

FIG. 3 is an elevational view of a bottle or similar article showing a second embodiment of our new design, the view from the opposite side being the mirror image of that shown;

FIG. 4 is a bottom plan view thereof;

FIG. 5 is an elevational view of a bottle or similar article showing a third embodiment of our new design, the view from the opposite side being a mirror image of that shown; and

FIG. 6 is a bottom plan view thereof.

The dominant features of our design reside in the heavily shaded areas seen below the horizontal line near the bottom in the elevational views.

This is a continuation of our design applications Ser. Nos. 16,721, 16,722 and 16,724, each filed Apr. 14, 1969, now abandoned.

We claim:

The ornamental design for a bottle or similar article, as shown and described.
